SYSTEM FOR STARTING AND OPERATING
GASEOUS DISCHARGE DEVICESJoseph G. Sola, Oak Park, Ill., assignor to Sola
Electric Co., Chicago, Ill., a corporation of
Delaware

Application March 10, 1939, Serial No. 280,932

12 Claims. (Cl. 176—124)

My invention relates to electric gaseous discharge devices and particularly to an improved arrangement by means of which such devices may be started and operated satisfactorily.

5 One of the objects of my invention is to provide an improved arrangement of this type by means of which the electrodes in an electric gaseous discharge device will be heated to a temperature at which the free electron emission 10 therefrom will support the normal discharge current and a voltage surge will then be applied to the tube between its electrodes for starting the tube in operation.

15 It is another object of my invention to provide an improved arrangement of this type by means of which the current for initially heating the electrodes to a temperature at which the free electron emission therefrom will support the normal discharge current will be interrupted and discontinued automatically after discharge 20 through the device has been started.

25 My invention contemplates the provision of an electromagnet having a winding in one of the supply lines on one side of one of the tube electrodes, a second winding between and in series with the electrodes and in magnetic opposition to the first winding and a movable armature controlling make and break switch means, and it is a further object of my invention to provide in 30 series with the second winding means adapted when the electrodes of the tube become heated to a temperature at which the free electron emission therefrom will support the normal discharge current to open automatically the switch means thereby cutting out the second winding and imparting a voltage surge to the tube to start normal discharge through the tube, the first winding serving to hold the armature in circuit-open 35 position during discharge through the tube.

40 It is a further object of my invention to provide an arrangement comprising but few parts which can be economically manufactured and assembled and which will be dependable and reliable in their automatic operation.

45 The invention consists of the novel constructions, arrangements and devices to be hereinafter described and claimed for carrying out the above stated objects and such other objects as will appear from the following description of a certain preferred embodiment illustrated in the accompanying drawing.

Referring now to the drawing, the gaseous discharge tube 10 is provided with electrodes 11 and 12 which are in the form of coiled filaments and which may be oxide coated for greater electron

emission. The tube is filled, at least after the filaments are heated, with a gas such as neon, or a mixture of gases such as helium and neon, or a source of vapor such as mercury. In starting a tube of this type it is first necessary to heat the electrodes to a temperature at which the electrons emitted therefrom are sufficient in number to support the normal discharge current between the electrodes, and then to apply a voltage surge to the tube between the electrodes 10 for starting discharge. The voltage of the surge is greater than the normal operating voltage of the discharge device and may be of short duration. Failure to heat properly the filaments in a tube of this type before initiating discharge 15 causes the discharge to be confined to one spot on each electrode whereby the electrodes are injured.

Electric current, preferably alternating current, is supplied to the discharge device 10 for 20 initially heating the filaments 11 and 12 and then for supporting discharge through the tube by supply lines 13 and 14. Supply line 13 is directly connected to filament 12 at its end 12a. An inductance or a choke coil 15 and a winding 16 25 of an electromagnet 17 are connected in series to the supply line 14. Winding 16 is in turn connected with the filament 11 at its end 11a by means of lead 18.

The electromagnet 17 has in addition to winding 16 two windings 19 and 20. Winding 19 has substantially the same number of turns but is in magnetic opposition to winding 16. Winding 20 which is a continuation of and is wound in the same direction as winding 19 has a shunting 30 resistor 21 connected across it and is grounded to the frame of the electromagnet at 22. The three windings 16, 19 and 20 are placed on the core portion 23 of the electromagnet as shown diagrammatically in the drawing. The resistor 21 is of a material such as nickel which has a 35 resistance that increases substantially with the temperature of the material. Winding 19 of the electromagnet is connected by means of lead 24 with the filament 11 at its end 11b as shown.

A movable armature 25 is pivoted at 23a to the frame of the electromagnet. The armature is held normally by a pull spring 26 against a stop 27 and spaced from the end 23b of the core bar. The armature carries a switch element 28 and when the armature is in the position shown in the drawing, the switch element 28 contacts with a second switch element 29 carried by a flexible arm 30, the arm being mounted on but insulated from the core of the magnet at 23c. 55

The arm 30 is connected by a lead 31 with the filament 12 at its end 12b. In the switch-closing position of the armature as shown in the drawing, the arm 30 is flexed upward slightly by the switch element 28 bearing on the switch element 29 and good contact between the switch elements is thus insured.

When a voltage is first applied between the supply lines 13 and 14 a heating current flows for 10 heating the filaments 11 and 12, the circuit being from line 14 through inductance 15, winding 16, lead 18, filament 11, lead 24, winding 19, winding 20 and resistor 21, electromagnet core 23, armature 25, switch element 28, switch element 29, arm 30, lead 31, filament 12 and finally to supply line 13. The windings 16 and 19 are connected in this circuit in opposition to each other and the net result of the heating current flowing through both windings is a magnetic flux substantially equal to 20 zero. The resistor 21 is initially in a cold state and has a resistance much less than that of the parallel winding 20. The greater portion of the heating current, therefore, flows through the resistor rather than through the winding 20. The 25 portion which does flow through winding 20 is so small that it does not produce a magnetic flux in the core bar 23 great enough to pull the armature 25 down to the core bar against the action of the spring 26. However, the resistance 21 quickly 30 heats up due to the action of the current passing through it and its resistance becomes greater and greater. More and more current flows through winding 20 producing a greater and greater resultant magnetic flux in the core bar 23. This 35 magnetic flux soon becomes great enough to cause the armature 25 to be pulled to the core, against the action of the spring 26, and the contact between the switch elements 28 and 29 is thus broken.

40 The sudden breaking of the circuit through the coils 19 and 20 of the electromagnet causes the magnetic flux in the core to decrease suddenly, producing a relatively high voltage surge in winding 16. This voltage surge added to the normal 45 line voltage causes discharge to take place directly between the electrodes 11 and 12. Once started, the discharge continues and the operating current flowing through winding 16 produces a magnetic flux in the core which acts to hold the armature in 50 switch-opened position, and the circuit through the winding 19, the winding 20 and resistor 21, and the lead 31 connecting the filaments 11 and 12 remains open. There is, therefore, no power loss 55 in those parts during discharge, and the resistor 21 consequently cools to the temperature of the surrounding atmosphere.

When the operating discharge circuit is opened, as by switching off the device, the current discontinues to flow through holding coil 16, and the 60 armature 25 under the action of spring 26 moves upwardly, thus again bringing the switch elements 28 and 29 into contact and completing the heating circuit. The arrangement is then again ready for the application of voltage to the supply leads for 65 heating the filaments and starting discharge, and the cycle of operations is repeated.

The resistor 21 is selected with due consideration to the characteristics of the other circuit elements including the winding 20 and the filaments 11 and 12. The resistor has such a resistance when cold, that is to say, such a temperature coefficient of resistance, and such heat radiating properties that it will heat up and in conjunction with winding 20 cause the armature 25 to move 70 toward the core bar and open the switch elements 75 toward the core bar and open the switch elements

when or immediately after the filaments 11 and 12 have reached a temperature at which they emit sufficient electrons to support the normal discharge current between the electrodes.

The inductance 15 is suitable with alternating 5 current and acts to stabilize the discharge through the gaseous discharge device. If direct current is used for the arrangement, a resistor should be used in place of the inductance.

It will be apparent from the foregoing description that my improved arrangement is of simple construction. The necessary parts may be economically manufactured and assembled on a production basis. The arrangement is entirely automatic in its operation, the electrodes of the tube 15 are safeguarded by being preliminarily heated to a temperature at which the free electron emission therefrom will support the normal discharge current before the tube is placed in operation. Upon switching off current to the gaseous discharge 20 tube the make and break switch means associated with the electromagnet immediately close since current in that case no longer flows through the holding coil 16. When current is again turned on it will not discharge directly from one electrode to 25 the other in the tube unless the electrodes are at the desired operating temperature, in such case the current will flow through the heating circuit including the second winding 19 and the resistor 21 and the third winding 20 until the electrodes 30 are at a temperature at which the free electron emission therefrom will support the normal discharge current.

I do not intend to limit the invention to the details shown and described, except only in so far 35 as certain of the appended claims are specifically so limited, as it will be obvious that modifications may be made without departing from the principles of the invention.

I claim:

1. In a system of the class described; the combination of an electric gaseous discharge device having a cathode adapted to emit electrons when heated; circuit means connected with two supply lines for initially heating said cathode to a temperature at which the free electron emission therefrom will support the normal discharge current and then for supplying the operating current thereto; said circuit means including an electromagnetic switch having a holding coil in series with said cathode in one of said supply lines and a neutralizing coil between said cathode and the other supply line, and means for opening the switch and cutting out the neutralizing coil when the temperature of the cathode reaches the point 5 at which the free electron emission therefrom will support the normal discharge current, the holding coil operating to hold the switch open during the discharge through the device.

2. In a system of the class described; the combination of an electric gaseous discharge device having a cathode adapted to emit electrons when heated; circuit means connected with two supply lines for initially heating said cathode to a temperature at which the free electron emission therefrom will support the normal discharge current and then for supplying the operating current thereto; said circuit means including an electromagnet having a holding coil in series with said cathode in one of said supply lines, a neutralizing coil between the cathode and the other supply line and a movable armature carrying a switch element, a second switch element adapted to engage said first switch element to close the circuit therethrough, means tending to hold the arma-

- ture in circuit closing position, and means for separating said switch elements and cutting out the neutralizing coil when the temperature of the cathode reaches the point at which the free electron emission therefrom will support the normal discharge current, the holding coil operating to hold the armature in open circuit position during the discharge through the device.
3. In a system of the class described; the combination of an electric gaseous discharge device having a cathode adapted to emit electrons when heated; circuit means connected with two supply lines for initially heating said cathode to a temperature at which the free electron emission therefrom will support the normal discharge current and then for supplying the operating current thereto; said circuit means including an electromagnet having a holding coil in series with said cathode in one of said supply lines, a neutralizing coil between the cathode and the other supply line, a third coil in series with said neutralizing coil, a resistor in parallel with said third coil and a movable armature carrying a switch element, a second switch element adapted to engage said first switch element to close the circuit therethrough, means tending to hold the armature in circuit closing position, said resistor initially carrying sufficient current around said third coil to render it inoperative but upon the temperature of the cathode reaching the point at which the free electron emission therefrom will support the normal discharge current the resistance of said resistor is such that said third coil becomes operative to cause the armature to move into open circuit position thereby rendering the holding coil effective and cutting out the other two coils.
4. In a system of the class described; the combination of an electric gaseous discharge device having a cathode adapted to emit electrons when heated; circuit means connected with two supply lines for initially heating said cathode to a temperature at which the free electron emission therefrom will support the normal discharge current and then for supplying the operating current thereto; and means for supplying a delayed voltage surge to said discharge device comprising an electromagnet having a winding in series with said cathode in one of said supply lines and a second winding connected between said cathode and the other supply line and in magnetic opposition to the first winding, make and break switch means in series with said second winding, and means for opening said switch means and cutting out said second winding when the temperature of the cathode reaches the point at which the free electron emission therefrom will support the normal discharge current, the first winding operating to hold the switch means open during the discharge through the device.
5. In a system of the class described; the combination of an electric gaseous discharge device having a cathode adapted to emit electrons when heated; circuit means connected with two supply lines for initially heating said cathode to a temperature at which the free electron emission therefrom will support the normal discharge current and then for supplying the operating current thereto; and means for supplying a delayed voltage surge to said discharge device comprising an electromagnet having a holding coil in series with said cathode in one of said supply lines, a neutralizing coil between the cathode and the other supply line and a movable armature carrying a switch element, a second switch element adapted to engage said first switch element to close the circuit therethrough, means tending to hold the armature in circuit closing position, and means for separating said switch elements and cutting out the neutralizing coil when the temperature of the cathode reaches the point at which the free electron emission therefrom will support the normal discharge current, the holding coil operating to hold the armature in open circuit position during the discharge through the device.
6. In a system of the class described; the combination of an electric gaseous discharge device having a cathode adapted to emit electrons when heated; circuit means connected with two supply lines for initially heating said cathode to a temperature at which the free electron emission therefrom will support the normal discharge current and then for supplying the operating current thereto; and means for supplying a delayed voltage surge to said discharge device comprising an electromagnet having a holding coil in series with said cathode in one of said supply lines, a neutralizing coil between the cathode and the other supply line, a third coil in series with said neutralizing coil, a resistor in parallel with said third coil and a movable armature carrying a switch element, a second switch element adapted to engage said first switch element to close the circuit therethrough, means tending to hold the armature in circuit closing position, said resistor initially carrying sufficient current around said third coil to render it inoperative but upon the temperature of the cathode reaching the point at which the free electron emission therefrom will support the normal discharge current the resistance of said resistor is such that said third coil becomes operative to cause the armature to move into open circuit position thereby rendering the holding coil effective and cutting out the other two coils.
7. In a system of the class described; the combination of an electric gaseous discharge tube having in each end an electrode adapted to emit electrons when heated; circuit means connected with two supply lines for initially heating said electrodes to a temperature at which the free electron emission therefrom will support the normal discharge current therebetween and then for supplying the operating current thereto; said circuit means including an electromagnetic switch having a holding coil in series in one of the supply lines on one side of one of said electrodes and a neutralizing coil in series with and between said electrodes, and means for opening the switch and cutting out the neutralizing coil when the temperature of the electrodes reaches the point at which the free electron emission therefrom will support the normal discharge current, the holding coil operating to hold the switch open during the discharge between the electrodes through the tube.
8. In a system of the class described; the combination of an electric gaseous discharge tube having in each end an electrode adapted to emit electrons when heated; circuit means connected with two supply lines for initially heating said electrodes to a temperature at which the free electron emission therefrom will support the normal discharge current therebetween and then for supplying the operating current thereto; said circuit means including an electromagnet having a holding coil in one of said supply lines on one side of one of said electrodes, a neutralizing coil in series with and between the electrodes and a movable armature carrying a switch element, a

second switch element adapted to engage said first switch element to close the circuit therethrough, means tending to hold the armature in circuit closing position, and means for separating 5 said switch elements and cutting out the neutralizing coil when the temperature of the electrodes reaches the point at which the free electron emission therefrom will support the normal discharge current, the holding coil operating to hold the armature in open circuit position during the discharge between the electrodes through the tube.

9. In a system of the class described; the combination of an electric gaseous discharge tube having in each end an electrode adapted to emit 10 electrons when heated; circuit means connected with two supply lines for initially heating said electrodes to a temperature at which the free electron emission therefrom will support the normal discharge current therebetween and then for 15 supplying the operating current thereto; said circuit means including an electromagnet having a holding coil in one of said supply lines on one side of one of said electrodes, a neutralizing coil in series with and between the electrodes and a movable armature carrying a switch element, a second switch element adapted to engage said first switch element to close the circuit therethrough, 20 means tending to hold the armature in circuit closing position, and means for separating said switch elements and cutting out the neutralizing coil when the temperature of the electrodes reaches the point at which the free electron emission 25 therefrom will support the normal discharge current, the holding coil operating to hold the armature in open circuit position during the discharge between the electrodes through the tube.

10. In a system of the class described; the combination of an electric gaseous discharge tube having in each end an electrode adapted to emit 30 electrons when heated; circuit means connected with two supply lines for initially heating said electrodes to a temperature at which the free electron emission therefrom will support the normal discharge current the resistance of said resistor is such that said third coil becomes operative to cause the armature to move into open circuit position thereby rendering the holding coil effective and cutting out the other two coils.

40

11. In a system of the class described; the combination of an electric gaseous discharge tube having in each end an electrode adapted to emit electrons when heated; circuit means connected with two supply lines for initially heating said electrodes to a temperature at which the free electron emission therefrom will support the normal discharge current and then for supplying the operating current thereto; and means for supplying a delayed voltage surge to said discharge tube comprising an electromagnet having a holding 45 coil in one of said supply lines on one side of one of said electrodes, a neutralizing coil in series with and between said electrodes, a third coil in series with said neutralizing coil, a resistor in parallel with said third coil and a movable armature carrying a switch element, a second switch element adapted to engage said first switch element to close the circuit therethrough, means tending to hold the armature in circuit closing position, said resistor initially carrying sufficient current 50 around said third coil to render it inoperative but upon the temperature of the electrodes reaching the point at which the free electron emission therefrom will support the normal discharge current the resistance of said resistor is such that said third coil becomes operative to cause the armature to move into open circuit position thereby rendering the holding coil effective and cutting out the other two coils.

the first winding operating to hold the switch means open during the discharge between the electrodes through the tube.

11. In a system of the class described; the combination of an electric gaseous discharge tube having in each end an electrode adapted to emit electrons when heated; circuit means connected with two supply lines for initially heating said electrodes to a temperature at which the free electron emission therefrom will support the normal discharge current and then for supplying the operating current thereto; and means for supplying a delayed voltage surge to said discharge tube comprising an electromagnet having a holding coil in one of said supply lines on one side of one of said electrodes, a neutralizing coil in series with and between the electrodes and a movable armature carrying a switch element, a second switch element adapted to engage said first switch element to close the circuit therethrough, 20 means tending to hold the armature in circuit closing position, and means for separating said switch elements and cutting out the neutralizing coil when the temperature of the electrodes reaches the point at which the free electron emission 25 therefrom will support the normal discharge current, the holding coil operating to hold the armature in open circuit position during the discharge between the electrodes through the tube.

12. In a system of the class described; the combination of an electric gaseous discharge tube having in each end an electrode adapted to emit electrons when heated; circuit means connected with two supply lines for initially heating said electrodes to a temperature at which the free electron emission therefrom will support the normal discharge current and then for supplying the operating current thereto; and means for supplying a delayed voltage surge to said discharge tube comprising an electromagnet having a holding 30 coil in one of said supply lines on one side of one of said electrodes, a neutralizing coil in series with and between said electrodes, a third coil in series with said neutralizing coil, a resistor in parallel with said third coil and a movable armature carrying a switch element, a second switch element adapted to engage said first switch element to close the circuit therethrough, means tending to hold the armature in circuit closing position, said resistor initially carrying sufficient current 35 around said third coil to render it inoperative but upon the temperature of the electrodes reaching the point at which the free electron emission therefrom will support the normal discharge current the resistance of said resistor is such that 40 said third coil becomes operative to cause the armature to move into open circuit position thereby rendering the holding coil effective and cutting out the other two coils.

JOSEPH G. SOLA.
